UNITED STATES PATENT OFFICE

JOHN J. CROWE, OF WESTFIELD, NEW JERSEY, ASSIGNOR TO AIR REDUCTION COMPANY, INCORPORATED, OF NEW YORK, N. Y., A CORPORATION OF NEW YORK

TORCH DEVICE

Application filed December 16, 1929. Serial No. 414,436.

The tips of cutting torches used for severing metal are designed to deliver a high velocity stream of oxygen. In my copending application Serial No. 411,239, filed December 3, 1929, I have disclosed a tip and a method of cutting wherein narrower kerfs and greater efficiency are secured by delivering the cutting stream through an orifice the divergence of which is such as to translate substantially all the pressure of the gas into kinetic energy. Thereby the velocity of the issuing stream is greatly increased and its width is reduced, because it spreads little or not at all on leaving the tip.

15 The Walker Patent 1,726,327 of August 27, 1929, discloses a torch tip having a flaring exit but adapted for a totally different kind of operation, calling for a broad, spreading stream of oxygen of lowered velocity. The 20 present invention relates to torch tips of that class, the object being to insure the delivery of an exceptionally wide stream. The uses of such a tip include the gouging out of defects in billets and blooms and the burning 25 away of rivet heads. For the latter purpose the broad stream is applied directly to the face of the rivet head, preheated by the familiar heating jets, with the result that part or all of the head is quickly consumed 30 without injury to the plate beneath.

In this invention I make use of a large oxygen passage provided with a flaring downstream portion adapted to deliver a large oxygen stream, as in the Walker patent, but in order to compel the stream to fill the flaring exit and to spread even more widely a device is inserted in the oxygen passage behind the flare or within the flare itself. This device, which may take several 40 forms, may have a passage which delivers a central portion of the flow substantially un-deflected and therefore at higher velocity than the surrounding portion of the stream.

In the accompanying drawings, forming 45 part hereof:

Fig. 1 is a longitudinal section of part of a torch head and of a tip therein embodying one form of the invention;

Fig. 2 is an enlarged side elevation of the 50 twisted blade device shown in Fig. 1;

Fig. 3 is a fragmentary longitudinal section of a torch tip in which vanes having twisted tips are employed for producing a whirling motion of the oxygen and causing the stream to fill the flaring exit;

Fig. 4 is an enlarged side elevation of the deflecting device shown in Fig. 3;

Fig. 5 is a plan view of the same device;

Fig. 6 is a view like Fig. 3 showing a device consisting of a plug having passages drilled 60 to direct the oxygen into the flaring chamber in tangential diagonal directions;

Fig. 7 is an enlarged side elevation of the device shown in Fig. 6;

Fig. 8 is a plan view of Fig. 7;

Fig. 9 is a view like Fig. 3 showing a propeller form device supported in the narrower portion of the flare;

Fig. 10 is a view like Fig. 3; the deflecting device employed being a body supported in 70 the flaring exit;

Fig. 11 is a similar view, showing the deflector provided with a central through passage;

Fig. 12 is an enlarged longitudinal section 75 of the device shown in Fig. 11; and

Fig. 13 is a fragmentary longitudinal section of a tip containing a device like that shown in Figs. 10—12, but having a central longitudinal passage terminating in inclined 80 exits.

The tips, which are marked 2 in the several views, have large central oxygen passages 3, the downstream portions 4 of which are broadened in a decided flare, so that the oxygen stream is delivered from a much enlarged round opening in the extremity of the tip. The tips have usual preheating jet passages 5, which may be provided at the rear end of the tip with inlets 6 and 7 for oxygen and fuel gas, respectively. The tip is adapted 85 to be inserted in a cutting torch head 8 having supply passages 9, 10 and 11 for cutting oxygen, heating oxygen and fuel gas, respectively.

In Fig. 1 a twisted strip of metal 12 is inserted firmly into the passage 3 just behind the flaring portion 4 and projecting into that portion. This device deflects the oxygen stream, causing it to whirl and spread out 100

evenly in the flaring exit, so that the mouth is filled by the stream. The stream which issues from the tip is consequently as wide as the delivery opening and tends to spread even more widely.

5. In Fig. 3 a four-winged vane device 12^a is introduced into the oxygen passage at the narrow end of the flare, the tips of the vanes being twisted to produce an effect similar to that just described.

10. In Fig. 6, the means for directing the oxygen outward to the wall of the flaring exit is a plug 12^b having diagonal passages 13 drilled in planes that may be described as tangential, 15 in order to impart a whirling or lateral motion to the oxygen on entering the flare.

15. In Fig. 9 a propeller like device 12^c is supported within the flaring exit by a stem 14 held in spiders 15. This device may be either 20 stationary or rotary.

20. In Fig. 10 a pear-shaped body 12^d on the end of a stem 16 is supported from spiders 15. This body is disposed within the narrow end of the flare and serves to deflect the oxygen flowing around it outward to the wall of the flare. Devices of other shapes and sizes for spreading the oxygen stream may be employed, and their location is not confined to the narrow end of the flaring exit.

30. In Fig. 11 the body 12^e and its stem have a straight central passage 17 for conducting a central portion of the stream and delivering it in the axial direction within the flare. In this way the broad stream of oxygen discharged from the tip may be caused to have a core traveling at higher velocity than the surrounding gas.

35. In Fig. 13, a similar form of a device 12^f has a central passage 17 which branches into a plurality of inclined exits 18 opening through the sides of the bulbous body. By varying the direction of these exits the spreading effect can be made more or less pronounced and varying degrees of turbulence can be 45 produced.

40. Other forms of the invention will suggest themselves.

I claim:

1. A torch device of the character described 50 having an oxygen passage provided with an enlarged downstream portion terminating in a large opening from which the oxygen stream is delivered into the atmosphere, and means for directing the oxygen outward in 55 said enlarged portion in order to insure a wide issuing stream.

2. A torch device of the character described 60 having an oxygen passage provided with a flaring downstream portion terminating in a large opening, and means in said passage at the region of said flaring portion to direct the oxygen outward to the wall of said portion in order to insure a wide issuing stream.

65. 3. A torch device of the character described 65 having an oxygen passage provided with a

flaring downstream portion terminating in a large opening, and means in said passage at the region of said flaring portion to impart a swirling motion to the oxygen.

4. A torch device of the character described 70 having an oxygen passage provided with a flaring downstream portion terminating in a large opening, and a twisted member in said passage at the region of said flaring portion.

5. A torch device of the character described 75 having an oxygen passage provided with a flaring downstream portion terminating in a large opening, and a device in said passage at the region of said flaring portion formed to direct the oxygen passing around the device to the wall of said flaring portion, said device also having an internal passage through it.

6. A torch device of the character described 80 having an oxygen passage provided with a flaring downstream portion terminating in a large opening, and a device in said passage at the region of said flaring portion constructed to direct the oxygen outward to the wall of said portion and also having a channel 90 for directing a central part of the flow into said flaring portion substantially without deflection.

7. A torch device of the character described 95 having an oxygen passage provided with a flaring downstream portion terminating in a large opening, and a device in said passage at the region of said flaring portion constructed to direct the oxygen in part outward to the wall of said portion and to deliver a central 100 portion of the stream in a more forward direction.

JOHN J. CROWE.
